UNITED STATES PATENT OFFICE.

SIEGMUND STIEGLITZ, OF NEW YORK, N. Y.

GAME-COUNTER.

SPECIFICATION forming part of Letters Patent No. 437,057, dated September 23, 1890.

Application filed April 17, 1890. Serial No. 348,385. (No model.)

To all whom it may concern:

Be it known that I, SIEGMUND STIEGLITZ, a citizen of the United States, residing at New York, in the county and State of New York, 5 have invented new and useful Improvements in a Case or Receptacle for Cards and other Objects, of which the following is a specification.

This invention relates to a case or receptacle for receiving such objects as playing-cards, score-cards, dominoes, and other objects, and by means of this invention the score or progress of a game can be easily noted, as set forth in the following specification and claims 15 and illustrated in the accompanying drawings, in which—

Figure 1 is a face view of the case-cover. Fig. 2 is a view of the case-bottom. Fig. 3 is a transverse section of Fig. 1. Fig. 4 is a section along $\alpha\alpha$, Fig. 3. Figs. 5 and 6 are perspective views of slides.

The case or receptacle may be of any well-known suitable form.

In the drawings the case is shown in the 25 form of a box provided with a cover sitting over the box. The face or top A of the cover is shown as having a number of slides C—one or more—which are placed on the inner or under side of said face A. The box-bottom 30 B is shown as having a number of slides D—one or more—which are placed on the outer side of said bottom B. The slides C D travel in guides E, which are readily formed by striking or cutting tongues or clips out of the 35 face A and bottom B and pressing said clips either outward or inward, according as the slide is to be placed on the outside or the inside of the bottom B or face A. Each slide C has a designation, such as a number or 40 character, and the face A has a sight-opening F for the designation on each slide. When the slide is moved to its exposing position, its designation is exposed through the opening F—as, for example, in the case of the slides 45 bearing the designations 10 and 100, Fig. 1. The remaining slides in Fig. 1 are shown in their concealing position, so that their designations are hidden from view. Each slide C has a handle G, which enables the slide to 50 be operated from the outside of the case as each handle G projects through a slot H in the face A. The slot H forms a guide for the

handle, and also acts as a stop to properly limit the movement of the slide and handle. Each slide D has a designation, such as a number or mark. The guides E overlap the slides D. When the slide is moved to its exposing position, the designation on the slide is exposed—as, for example, in the case of the slides bearing the designations 10 and 70, Fig. 2. 55 When the slides are moved to their concealing position, as is the case with the remaining slides in Fig. 2, the guides E will conceal or cover the designations on the slides D, in whole or in part. The slides D have handles 60 I, which enable the slides to be operated, and said handles also form stops for limiting the movements of the slides. The slides D with their handles, as also the slides C with their handles, are readily formed or shaped from 65 sheet metal.

The bottom B may have designations—such as marks or numbers—either placed or marked directly on the bottom or upon paper or other substance placed within the bottom, so that 70 the designations will appear through sight-openings K in the bottom. By moving the slides D to the exposing positions the designations of the bottom B will be exposed, and by moving the slides to their concealing position said designations are concealed. 75

What I claim as new, and desire to secure by Letters Patent, is—

1. The combination, with a case or receptacle for cards and other articles, having a 80 designating character, of a slide-bearing or a similar designating character, and a guide located on the exterior of the case or receptacle, and overlapping the slide to conceal the designation on the slide when the latter is 85 moved to cover the designating character on the case or receptacle, substantially as described.

2. A case or receptacle for cards and other objects, provided with a designation, one or 90 more, a slide D, one or more, for concealing said designation, said slide also bearing a designation, and a guide on the exterior of the case or receptacle made to overlap the slide, so as to conceal the designation on the 95 slide when the slide is moved to cover the designation on the case or receptacle, substantially as described.

3. A case or receptacle for cards and other

objects, provided with a sight-opening K, one or more, and a designation placed behind said opening, a slide D, one or more, for concealing said designation, said slide also bearing 5 a designation, and a guide located on the exterior of the case to overlap the slide and conceal the designation on the slide when the slide is moved to cover the sight-opening in the case or receptacle, substantially as de-
scribed.

4. The combination, with a case or receptacle for cards or other articles, having a designating character, of a slide on the exterior of the case or receptacle, provided with out-

wardly-bent handle ends I and a designating 15 character, and a guide on the exterior of the case or receptacle for concealing the designating character on the slide when the latter is moved to cover the designating character on the case or receptacle, substantially as 20 described.

In testimony whereof I have hereunto set my hand in the presence of two subscribing witnesses.

SIEGMUND STIEGLITZ.
